UNITED STATES PATENT OFFICE.

ALBERT T. ZABRISKIE, OF PASSAIC, NEW JERSEY.

AUTOMATIC CALENDAR.

1,073,206.

Specification of Letters Patent. Patented Sept. 16, 1913.

Application filed December 26, 1912. Serial No. 738,524.

To all whom it may concern:

Be it known that I, ALBERT T. ZABRISKIE, a citizen of the United States, residing at Passaic, in the county of Passaic and State of New Jersey, have invented certain new and useful Improvements in Automatic Calendars, of which the following, taken in connection with the accompanying sheet of drawings, is a complete and concise description.

10 The present invention relates to certain new and useful improvements in calendars, and has for its primary object to provide a mechanical calendar which embodies novel features of construction whereby it can be readily set for any month of any year within a ten thousand year limit.

15 The object of the invention is to provide a calendar of this character which is simple and inexpensive in its construction, which can be easily and quickly set for the desired month of the particular year, and which does not require any arithmetical or mental calculations on the part of the operator.

20 25 A still further object of the invention is to provide a mechanical calendar which is compact in its construction and can be very inexpensively manufactured so as to be susceptible of use for advertising purposes.

30 35 With these and other objects in view, the invention consists in certain combinations and arrangements of the parts as will more fully appear as the description proceeds, the novel features thereof being pointed out in the appended claims.

35 For a full understanding of the invention, reference is to be had to the following description and accompanying drawings, in which:—

40 Figure 1 is a plan view of the calendar, showing the same as set for the month of January 1912. Fig. 2 is a plan view of the calendar with the face thereof removed. Fig. 3 is a sectional view on the line 3—3 of Fig. 1. Fig. 4 is a plan view showing the calendar as set for the month of December 1912, and Fig. 5 is a rear view showing the table to which reference is made when setting the calendar.

45 50 Corresponding and like parts are referred to in the following description and indicated in all the views of the drawings by the same reference characters.

55 Specifically describing the present embodiment of the invention, the numeral 1 designates the face of the calendar, the said face

being formed with the sight openings 2 and 3 and being adapted to have any suitable advertising matter placed thereon. The sight opening 3 is arranged immediately under the sight opening 2, with a strip 4 interposed between the two sight openings. The month slide 6 is mounted under the sight opening 2, while the key slide 7 is mounted under the sight opening 3. 65

Any suitable means may be provided for mounting the slides 6 and 7 back of the calendar face 1, and in the present instance they are shown as arranged in slotted portions 8 of an intermediate thickness of material 9 which is interposed between the face 1 and a backing 10. Each of the slides 6 and 7 is provided with an eyelet or finger piece 11 by means of which the slide can be moved back and forth within the guideway 70 provided for the same for the purpose of setting the calendar.

The portion of the calendar face 1 immediately above the upper edge of the sight opening 2 is subdivided into seven spaces 80 having the days of the week printed or indicated therein, as indicated at 12, in the usual manner. The strip 4 between the two sight openings 2 and 3 is subdivided into seven vertical columns which are arranged directly 85 under the before mentioned spaces having the days of the week printed therein. In the first column appears the word May, in the second column appears the word Aug., in the third column appears the words Feb., 90 Mar. and Nov., in the fourth column appears the word June, in the fifth column appear the words Sept. and Dec., in the sixth column appear the words Apr. and July, in the seventh appear the words Oct. and Jan. 95 These words indicate the twelve months of the year, and under each of the words is the numeral designating the number of days in the month. Under the word Feb. are the two numerals 28 and 29 L, indicating that 100 February usually has 28 days although on leap year it has 29 days.

The month slide 6 which is movable under the view opening 2, is shown as subdivided by the lines 13 into thirteen vertical columns, exactly seven of the vertical columns being visible through the sight opening 2 at the same time and the said columns corresponding in width to the spaces over the top of the sight opening in which the days of 110 the week appear. There are six horizontal rows of figures upon the month slide 6, the

said figures being adapted to designate the day of the month in the usual manner. In the upper horizontal column the first eight spaces are blank while the last five spaces 5 contain the numerals 1 to 5 inclusive. In the second horizontal column, the first space is blank, the remaining spaces being provided with the numerals 1 to 12 inclusive. The third horizontal column is provided 10 with the numerals 7 to 19 inclusive, the fourth horizontal column is provided with the numerals 14 to 26 inclusive, the fifth horizontal column is provided with the numerals 21 to 31 inclusive, the last two spaces 15 being blank. The sixth horizontal column is provided with the numerals 28 to 31 inclusive, the last nine spaces being blank. It will be observed that following down the various vertical columns of figures, the numerals 20 increase by sevens in the same manner which is customary upon calendars, and regardless of the position to which the slide 6 may be moved, the characters thereon will read continuously from 1 to 31 when following out the successive horizontal columns 25 in the usual manner employed in connection with calendars. In the present instance the finger piece 11 of the month slide 6 is arranged at the bottom of the seventh vertical 30 column.

The key slide 7 is shown as divided into thirteen spaces corresponding to the vertical columns of the month slide 6, the said spaces being provided with the key letters which, 35 reading from left to right, have the following order:—E, F, G, A, B, C, D, E, F, G, A, B, C. The finger piece 11 of this key slide is arranged at the bottom of the seventh space of subdivision.

40 In setting the calendar, a key or table is employed, such as is shown by Fig. 5. This table is provided with the columns 14 in which appear the numerals from 0 to 99 inclusive, the said numerals indicating the 45 various years of each century. It will be observed that the numeral corresponding to every fourth or leap year appears twice, the letter L appearing opposite one of the occurrences. The year columns 15 and century columns 16 are arranged at the side of 50 the columns 14 and contain key letters corresponding to the letters upon the key slide 7.

In order to set the calendar it is first necessary 55 to refer to the table and run down the column 14 until the numeral therein is reached which corresponds to the year of the century. For the year 1912 the required numeral would be the numeral 12, since this 60 is the twelfth year of the particular century. This also happens to be leap year so that we find both the numeral 12 and the numeral 12 L, the character B appearing in the column 15 after the numeral 12 L, while the 65 character A appears in the year column 15

after the numeral 12. In the case of a leap year, the key letter B which appears opposite the numeral 12 L would be employed for setting the calendar for the months of January and February only, the key letter for the year not marked L being employed for setting the calendar for the other months. In order to set the calendar for January 1912, the key slide 7 would be moved to bring the key letter B, said letter having 70 been ascertained by reference to the key table, under the January column of the intermediate strip 4 between the sight openings 2 and 3. The operator would next run down the column 14 until he came to the numeral 19, the said numeral being the first half of the date 1912 and indicating the number of centuries which have already lapsed. In the century column 16 opposite this numeral 19, the key letter B will be 75 found and the month slide 6 will be moved to bring the finger piece 11 thereof over the key letter B wherever it may appear upon the key slide 7. The calendar will then be properly set for the month of January in the year 1912. This position of the various parts is shown by Fig. 1.

In order to set the calendar for December 1912, the operator runs down the column 14 to the numeral 12, and finds the key 80 letter A in the year column 15 opposite this numeral. Although this is a leap year it will be remembered that the key letter for the leap year is only employed in connection with the months of January and February. The key slide 7 is now moved to bring the character A thereon under the December column of the strip 4. By again running down the column 14 to the numeral 19, the said numeral indicating the number of centuries which have already lapsed and corresponding to the first part of the date 1912, we find the key letter B in the century column 16 opposite the numeral 19. The month 85 slide 6 is now moved to bring the finger piece 11 thereof directly over the key letter B of the key slide. This position of the parts is shown by Fig. 4, and the calendar is then correctly set for the month of December in the year 1912.

100 It will thus be obvious that in order to set the calendar, the key slide 7 is first moved to bring the correct key letter thereof, previously ascertained by reference to the table, under the correct month column of the strip 4, the month slide 6 being next moved to bring the finger piece 11 thereof directly over the correct key letter of the key slide 7, the said key letter being also ascertained by reference to the table. In this manner the calendar can be quickly set for any desired month and it can be quickly ascertained upon what week day any particular date in the past or future either has 105 fallen or will fall.

130

By reference to the bottom of the table it will be seen that from 1709 to September 2, 1752, the century key would be the letter C, while from September 14, 1752 to 1799, the 5 century key would be the letter F.

Having thus described the invention, what I claim as new and desire to secure by Letters Patent, is:—

1. A calendar including a face having a 10 tabular arrangement of the months of the year and also a tabular arrangement of the days of the week thereon, a key slide mounted upon the face and having key characters thereon, the said key slide being adapted 15 to be set to bring the characters thereon in a predetermined relation to the tabular arrangement of the months of the year, and a months slide mounted upon the face and formed with a marked portion which is 20 adapted to be set in a predetermined relation to the characters of the key slide, the said months slide being formed with a tabular arrangement of numerals which then bear the proper relation to the before mentioned 25 tabular arrangement of days of the week upon a calendar face.

2. A calendar including a face provided with a pair of view openings and having a tabular arrangement of the days of the week 30 at the edge of one of the view openings and a tabular arrangement of the months of the year at the edge of the other of the view openings, a key slide mounted under the second mentioned opening and having key 35 characters thereon adapted to be set in a predetermined relation to the before mentioned tabular arrangement of the months of the year upon the calendar face, and a months slide mounted under the first mentioned 40 view opening and adapted to be set in a predetermined relation to the key slide, the said months slide having a tabular arrangement of numerals thereon which designate the days of the month and are then arranged 45 in a proper relation with respect to the tabular arrangement of days of the week upon the calendar face.

3. A calendar including a face having a pair of view openings therein and provided

with a tabular arrangement of the days of 50 the week at the edge of one of the view openings, and a tabular arrangement of the months of the year at the edge of the other view opening, a key slide mounted under the second view opening and provided with a 55 series of key characters, a predetermined one of which is adapted to be brought opposite the desired month in the months column, and a months slide mounted under the first mentioned view opening and adapted to be 60 set in a predetermined relation to the characters upon the key slide, the said months slide being provided with a tabular arrangement of numerals for designating the days of the month and the said numerals then 65 bearing the proper relation to the tabular arrangement of the days of the week on the face of the calendar.

4. A calendar including a face provided with a pair of view openings which are arranged side by side and separated by a strip, the said strips between the view openings having a tabular arrangement of the months thereon while a tabular arrangement of the days of the week is provided at the opposite 75 edge of one of the view openings, a key slide mounted under the opposite view opening and provided with a series of key characters, a predetermined one of which is adapted to be brought opposite the required month in 80 the tabular arrangement of months upon the strip between the view openings, and a months slide mounted under the first mentioned view opening and having a marked portion thereof which is adapted to be 85 brought opp. site a predetermined key character upon the key slide, the said months slide being provided with a tabular arrangement of numerals corresponding to the days of the month and the said tabular arrangement of the numerals then bearing the proper relation to the tabular arrangement 90 of the days of the week at the edge of the view opening.
